UNITED STATES PATENT OFFICE.

FLOSSIE G. ALLEBAUGH, OF NEDERLAND, COLORADO.

DESIGN FOR A TABLE ORNAMENT.

Application filed March 28, 1925. Serial No. 12,941. Term of patent 3½ years.

To all whom it may concern:

Be it known that I, FLOSSIE G. ALLEBAUGH, a citizen of the United States, residing at Nederland, in the county of Boulder and State of Colorado, have invented a new, original, and ornamental Design for Table Ornament, of which the following is a specification, reference being had to the accompanying drawing, forming part thereof.

The figure is a perspective view of a table ornament showing my new design.

What I claim is:

The ornamental design for a table ornament as shown.

In testimony whereof I have affixed my signature.

FLOSSIE G. ALLEBAUGH.
